DESIGN FOR A BATHTUB

Walter J. Kohler, Kohler, Wis.

Application June 1, 1936, Serial No. 62,937

Term of patent 14 years

To all whom it may concern:

Be it known that I, Walter J. Kohler, a citizen of the United States, residing at Kohler, in the county of Sheboygan and State of Wisconsin, have invented a new, original, and ornamental Design for Bathtubs, of which the following is a specification, reference being had to the accompanying drawing, forming part thereof.

I claim:

The ornamental design for a bathtub, as shown.

WALTER J. KOHLER.
